UNITED STATES PATENT OFFICE.

ERNEST F. MILLER, OF MOORES, PENNSYLVANIA, ASSIGNOR TO WESTINGHOUSE ELECTRIC & MANUFACTURING COMPANY, A CORPORATION OF PENNSYLVANIA.

METHOD OF MANUFACTURING TURBINE BLADES.

Application filed November 30, 1927. Serial No. 236,869.

My invention relates to blading for elastic fluid turbines and it has for an object, to improve the construction of such blading and also the method of manufacture thereof.

In view of the relatively large stresses which are set up due to centrifugal force, it has long been considered desirable to make turbine blades of a hollow construction. This is especially true with respect to the larger reaction blades, for with a given contour the hollow construction not only reduces the mass which is subject to centrifugal force, but it is also well adapted to withstand various bending stresses which occur in the operation of a turbine.

Furthermore, a more rigid construction for a given weight can be produced if the walls of a hollow blade are not of uniform thickness, but rather of greater thickness in the vicinity of the thinner edge portions of a blade. A construction of this type results in the disposition of relatively greater quantities of metal at great distances from the shorter transverse axis and thus, gives a blade considerable strength with respect to this axis, while at the same time, sufficient metal is disposed in the front and back walls to assure sufficient strength about the longer transverse axis. This thicker inlet and outlet edge portions are also advantageous, as these edges are subject to the greatest erosion. Moreover, a blade should be of simple construction so that it may be made with as few operations as possible and thus, be inexpensive to manufacture.

More particularly, therefore, an object of my invention is to provide a blade of light, and yet rigid construction, and which shall be inexpensive to manufacture, and to provide an improved method of making the same.

Apparatus exemplifying the features of my invention is shown in the accompanying drawings, forming a part of this specification, and wherein:

Figs. 1 and 2 are transverse sections of a blank, showing the manner in which different operations are performed thereon;

Fig. 3 is a transverse section of a blank on which the preliminary operations have been completed; and,

Fig. 4 is a transverse section of a completed blade.

According to my invention, a suitable solid bar section, or blank 10, which is, pref-

erably, a forging having substantially the exterior configuration of a finished blade, is cut lengthwise from end to end by suitable apparatus, such as the milling cutter 11, so as to form a longitudinally extending groove, 60 or channel 12, in the blank. An end miller 13 is then run down the length of the blank 10, the shank of the miller 13 extending through the groove 12, as shown in Fig. 2. The completion of these operations leaves the blank 65 10 substantially as shown in Fig. 3.

A strip 14, of a length corresponding to the length of the blank 10, is then fitted into the groove 12 and is secured to the remaining portions of the side walls of this groove in 70 any approved manner, preferably by means of silver solder. This operation completes the blade, except in so far as polishing, and like operations.

In this way, a hollow blade may be formed 75 from a solid forging, or the like, by performing only two relatively simple cutting operations. While the groove 12 may be cut in either the front or the back of the blade section 10, I prefer to cut this groove in the 80 back as shown as the back of the blade is less subject to the effects of erosion than the front. It will also be observed that, by selecting an end miller 13 of proper shape, the walls of the blade may be left thicker near 85 the edge portions which are thereby better enabled to withstand the effects of erosion and of bending.

While I have shown my invention in but one form, it will be obvious to those skilled 90 in the art that it is not so limited, but is susceptible of various changes and modifications without departing from the spirit thereof, and I desire, therefore, that only such limitations shall be placed thereupon 95 as are imposed by the prior art or as are specifically set forth in the appended claims.

What I claim is:

1. The method of producing a hollow impeller blade from a solid blank which comprises slotting the blank, undercutting the walls of the slot and then closing the slot. 100

2. The method of producing a hollow impeller blade from a solid blank which comprises cutting a slot in a convex surface of 105 the blank, undercutting the walls of the slot and then closing the slot.

3. The method of producing a hollow impeller blade from a solid blank which comprises cutting a channel in the blank, cut- 110

- ting away sufficient portions of the walls of the channel to leave side walls of suitable thickness for a blade and fitting a strip of material to the channel for closing the same.
5. 4. The method of producing a hollow impeller blade from a solid blank which comprises cutting a channel in the blank, cutting away sufficient portions of the walls of the channel to leave side walls of suitable thickness for a blade, fitting a strip of material to remaining portions of the side walls of the channel for closing the same and securing the fitted strip to the remaining portions of said side walls by fusion of metal.
5. The method of producing a hollow impeller blade from a solid blank which comprises cutting a channel in the blank, removing sufficient portions of the side walls of the channel to leave front and back walls of suitable thickness and to leave a relatively greater thickness of material in the vicinity of the juncture of these walls and fitting a strip to the remaining portions of the side walls of the channel for closing the same.
- In testimony whereof, I have hereunto subscribed my name this 22nd day of Nov., 1927.

ERNEST F. MILLER.
